UNITED STATES PATENT OFFICE.

FERDINAND WENDL, OF NEW YORK, N. Y.

EXTENSION-TABLE.

1,294,734.

Specification of Letters Patent. Patented Feb. 18, 1919.

Application filed September 3, 1916. Serial No. 252,269.

To all whom it may concern:

Be it known that I, FERDINAND WENDL, a citizen of the United States, and a resident of New York, in the county and State of New York, have invented certain new and useful Improvements in Extension-Tables, of which the following is a specification.

This invention relates to improvements in extension tables and has as its special object to provide a table having an unbroken top securely engaged with its supporting frame, and a plurality of plate leaves which may be extended in the same plane as the top, at either or both ends thereof, whereby the capacity or available area of the table may be increased.

A further object is to provide means whereby the leaves are normally contained below the table top, when not in use, and which may be adjusted at the ends in a convenient manner, with the expenditure of a minimum of physical energy.

Another object is to provide means whereby the leaves, when in an extended position, are firmly held and supported, the joints between the leaves and the table top being drawn tightly together, so as to present no crevice or space therebetween.

These and other like objects of a similar nature are attained by the novel construction and combination of parts hereinafter described and shown in the accompanying drawings, forming a material part of this disclosure and in which—

Figure 1 is a side elevational view showing a table made in accordance with the invention.

Fig. 2 is an end view thereof.

Fig. 3 is a side elevational view showing the upper portion of the table, one leaf being extended at each end.

Fig. 4 is a similar view of the same, but showing two pairs of leaves extended at each end of the table.

Fig. 5 is a bottom plan view and section, the section being taken on line 5—5 of Fig. 4.

Fig. 6 is a longitudinal sectional view, taken on line 6—6 of Fig. 5.

Fig. 7 is a similar sectional view, taken on line 7—7 of Fig. 5, the table top being inclined permitting the entry of a leaf below, due to actuating the raising lever.

Fig. 8 is a bottom plan and sectional view, the section being taken on line 8—8 of Fig. 1.

Fig. 9 is a transverse sectional view taken 55 on line 9—9 of Fig. 8, and

Fig. 10 is an enlarged fragmentary sectional view showing the arrangement of one of the retarding detents used in construction.

60

In the drawings the table is shown to be supported upon four legs or columns 20, which may be any desired ornamental design whatever, connected near their lower ends by rigidly engaging brace elements 21. 65 The upper ends of the legs are fixedly secured at the inner corners of an open rectangular frame, comprised of side elements 24 and 26, secured together by any of the usual devices employed for such purposes. 70

At the center of this frame, and upon the upper side thereof, is firmly secured a cross piece 27, held by fastenings 28, its ends extending beyond the sides 24, to the full width of the table. Upon this cross piece 75 27, is supported the table top 30, the same being substantially integrally formed, its sides and ends extending marginally beyond the supporting frame. The table top is secured at a central point by a screw 31, passing through an opening formed in the center of the cross piece 27, the screw being loosely received therein, and acting as a guide for positioning the cover plate, its upper screw threaded end passing into the 80 plate 32, fixed in the lower side of the table top.

Formed near the ends of the cross piece 27, are slots 22 through which pass screws 34, threaded into the lower surface of the 90 table top, the heads of the screws being engaged upon the outer surface of bent flat springs 35, which normally hold the table top in close engagement with the upper surface of the cross piece 27, the slots being 95 provided to allow for contraction and expansion of the wood used in the table due to shrinkage, etc.

The springs 35 permit the table top to be moved vertically a limited amount from the 100 cross piece and in the intervening space normally existing between the lower side of the table top and the upper edges of the frame element are positioned the leaves or extensions 38 and 40, respectively inner and 105 outer, the same being of uniform thickness and width and normally supported upon the upper edges of the frame sides 24.

- Secured centrally upon the lower surface of the inner pair of leaves 38, are brackets 41, held by screws 42, the inner extending elements 43, of the brackets having fixed pins 44 upon which are journaled bell-crank levers, their longer ends 45, being adapted to make contact with the lower surface of the table top, near its outer end edges, while the other, right angled, downturned arms 46, of the bell-crank levers are engaged by pivots 47, with links 48, which extend outwardly beyond the table, below the leaves 38 and 40, being supported and guided in clips 49, secured to the lower sides of the outer leaves 40, the links terminating in projections 50 adapted to be operated in the manner of a handle, the same extending through open slots 52, formed in the center of the upper edges of the end frame elements 26.
- Attached to the lower sides of the outer leaves 40, are the ends of horizontal support bars 56, the extremities of the bars having projections 57, used in the manner of handles in withdrawing the leaves, and have beveled outer surfaces 58. Recesses 60 are formed in the upper surfaces of the bars receptive of the inner leaves 38, the bars passing through rectangular openings 61 formed in the end frame elements 26 and extend, when the leaves are folded, nearly to the opposite end frame elements, as can best be seen in Fig. 8.
- Similarly engaged with the inner leaves 38, are other bars 62, arranged closely adjacent to the bars 56, and operated longitudinally with them by reason of their being engaged between projections 63, at the foot or the inner ends of the bars 56, and offset shoulders 64, formed near their outer, thickened ends, it being understood that these bars are arranged in pairs at both sides of the table; thus each pair of bars 56 and 62 move in unison as the leaves are extended.
- All of these bars normally rest upon the bottoms of the recesses 61, supporting the leaves upon which the cover plate 30 normally rests.
- In operation, when it is desired to extend one of the leaves it is accomplished by grasping the extending handles 57, withdrawing the same, whereupon both of the leaves 38 and 40, are retracted or brought outwardly, this action causes the inclined edges 58 to ride upon the bottom of the recesses 61, slightly raising the adjacent end of the table top 30, until the leaf 40, has passed its edge.
- The leaf 40 at that time is supported on the end of the bars 56, the inner portions of which contact with the cross piece 27, while the bottom of the bars rest in the recesses 61 thereby supporting the leaf in a firm and secure manner.

In order to hold the edges of the leaf and the table top tightly together, plates 66 are fixed in the lower surface to the inner bars 62, the same having concave seats or depressions 67, engageable with which are spherical headed, sliding detents 68, set in openings 70 appropriately formed in the end frame element 26, and pressed normally upward by the coiled compression springs 69, so as to engage in the depressions and draw the leaf tightly against the edge of the table top, the detents being held against loss by extending pins 70, operating in slots 71, formed in the frame elements upon their inner side, as can be best seen in Fig. 10.

Should it be required to extend the inner leaf 38, sufficient force is exerted to overcome the friction of the spring detents 68 and draw the leaves out, which operation raises the inner leaf 38 to the level of the leaf 40 and table top 30, the leaves being supported respectively upon the ends of the bars 56 and 62.

From the foregoing it will be seen the joint between the leaves is held tightly together by the detents as before described and in order to hold the edge of the leaves 38 in engagement with the edge of the table top, flat bent springs 75 are secured to the inner side of the frame ends 26, engageable with which are pins 76, set in the lower sides of the bars 56, the same making contact with the springs, drawing the leaves against the edge of the table top.

When it is desired to replace the leaves, it is accomplished by pulling upon the extending knobs 50 which, through the links 48, operates the bell-crank levers, so that the longer arms 45, contact with the lower side of the table top, raising the outer edge sufficient to allow the leaves to enter therebelow, whereupon the leaves may be pressed into their original position, the same action taking place whether one or both of the leaves are to be retracted.

When only the outer of the leaves is extended the link 48 rests in the central cut-out 78 of the inner leaf 38, which is also recessed, as at 79, to permit the bell-crank lever 45 to freely operate.

In order to prevent inadvertent raising of the outer leaves 40, pins 80, are set in their outer edges, the same engaging in recess 81, appropriately formed in the end walls of the frame, when the leaf is in a folded position, and similarly other pins 82 are secured to the support bars 56, maintaining the leaves level when the outer leaves are extended, the pins freely passing through the slots when the leaves are moved into either extended or retracted position and preventing their being raised inadvertently.

From the foregoing it will be seen that a table has been disclosed in which the leaves

may be extended or folded in an easy and convenient manner, when in a folded position presenting a neat and attractive appearance and when extending to be firmly supported.

Having thus described my invention what I claim as new and desire to secure by Letters Patent, is—

1. In an extension table, the combination with a frame and supports therefor, of a fixed cross-piece on said frame, a solid table top inclinably mounted on said cross-piece, a pair of bow springs resiliently clamping said top to said cross-piece, pairs of leaves normally interposed between said top and said frame, independent support bars for each of said leaves, said bars being arranged in interengaged pairs, each of the members of each pair being movable in a vertical plane independently of the other, bell-crank levers mounted on the inner of said leaves centrally of said frame adapted to raise the adjacent edges of said table top, means for actuating said levers, means for retracting said leaves, and means formed with said bars and said frame for automatically raising said leaves level with said table top when in an extended position.

2. In an extension table, the combination

with a frame and supports therefor, of a fixed central cross-piece on said frame, a solid table top mounted on said cross-piece, means permitting contraction or expansion of said top relative to said cross-piece, means permitting said top to be tilted in either direction, pairs of leaves normally disposed between said top and said frame at each side of said cross-piece, a pair of longitudinally extending bars rigidly secured to each of said leaves, said bars being normally contained within said frame, means for extending said leaves, means formed with said bars for raising said leaves level with said top when extended, said bars passing through recesses formed in the end elements of said frame, detents in said frame engageable with said bars as the outer leaves are withdrawn, other detents engageable with said bars when the inner leaves are withdrawn, and interengaging means formed with the support bars of said leaves whereby they are operated in unison longitudinally and independently movable vertically.

In testimony whereof I have signed my name to this specification.

FERDINAND WENDL.
